UNITED STATES PATENT OFFICE.

EITEL WILHELM THIELE, OF HOXTER-ON-THE-WESER, GERMANY.

MOLDING PRESS.

Application filed September 22, 1921. Serial No. 502,584.

To all whom it may concern:

Be it known that I, EITEL WILHELM THIELE, a citizen of Germany, and a resident of Hoxter-on-the-Weser, Westphalia, in the Republic of Prussia, Germany, have invented certain new and useful Improvements in Molding Presses, of which the following is a specification.

My present invention relates to molding-
10 presses, but more particularly to molding-
presses for transforming raw materials, sub-
sequently to be burnt in kilns or ovens, into
charging-blocks. To produce the latter from
raw cement-dust, lime-sandstone, etc, drop-
15 presses, table-presses and the like have been
employed hitherto. But such presses operate
in a vertical direction and therefore trans-
mit powerful blows to their foundations.

The construction of the modern vertical
20 kilns or ovens, which are charged at the top
and which discharge the burnt products auto-
matically at their bottom, makes it desirable
that presses employed for the production of
charging-blocks to be burnt in such kilns or
25 ovens should be erected in close proximity to
the mouth thereof. To employ here molding-
presses of the kind mentioned above, it would
be necessary to build solid foundations of
30 a height almost equal to that of the kiln or
oven utilized, which would cause exceedingly
high expenses.

To avoid these drawbacks I provide a
molding-press equipped with a molding-
drum rotating in a vertical plane and carry-
35 ing in its circumference a plurality of trans-
versely arranged pairs of moulds in which
operate horizontally disposed press-plungers
grouped in as many pairs as there are pairs
of moulds. The individual plungers of each
40 pair of plungers reciprocate in the moulds
cooperating with them in such a manner that
they are always working in alignment with,
but in opposition to each other, so that the
thrust of each plunger is neutralized by the
45 other plunger associated with it. By this
arrangement the foundation of the press is
protected against detrimental blows and the
whole pressure developed by the press-
plungers is profitably employed for the pro-
50 duction of charging-blocks.

To assure a continuous operation of the
molding-press, auxiliary elements, such as a
feed-hopper, a cover for successively closing
and opening said pairs of moulds automatic-
55 ally, ejectors for removing the moulded ob-
jects, and so forth, are provided and ar-

ranged partly at the circumference and partly
in the interior of said molding-drum in
such relation to said moulds and press-
plungers as to successively admit the raw
material to the molds, compress it in the
latter to charging-blocks, eject these charging-blocks from the press and transfer them
60 to the kiln or oven. On account of the pre-
ferred arrangement of molds and press-
plungers in pairs in combination with the
several elements cooperating therewith, my
improved molding-press shows a twin-like
65 construction and thus combines a remarkably
light weight with great strength and reliabil-
ity.

The movements of the plungers and other
movable elements are preferably produced by
the aid of inclined planes partly carried by
the frame of the press, and partly supported
70 by the driving-shaft of the molding-drum,
as will be more fully shown and explained
here-in-after and claimed in the appended
claims.

In the accompanying drawings, in which
one embodiment of my present invention
is shown by way of example:—

Figure 1 is a longitudinal sectional view
taken on line A—B of Figure 2.

Figure 2 is a cross-sectional view taken on
line C—D of Figure 1.

Figure 3 is an elevation of an end-plate of
the press-frame, and

Figure 4 is a side-elevation of the mold-
ing-press with the guard-plate removed, 90
whereas

Figure 5 is an end-elevation of the mold-
ing-press viewed in the direction of the
arrows shown in Figures 1 and 4.

The frame of the molding-press chiefly
consists of a tubular casing 1 and two stand-
ards 2 firmly held together by a plurality
of tie-rods 3. In the bearings 4 of these
standards the horizontally arranged driv-
ing-shaft 5 of a molding-drum 6 is jour-
naled and rotated by the aid of a belt-gear-
ing 7 and a worm-wheel-gearing 8, as indi-
cated in Figures 1, 4 and 5. In the circum-
ference of said molding-drum 6 a plurality
of transversely disposed channels 9 are ar-
ranged equidistant from each other. The

number of these channels and their config-
uration might, of course, differ from these
shown by way of example. Each of these
channels is bisected by a division-wall 10,
thus forming a corresponding number of pairs
of moulds or double-moulds 11, in which

the individual moulds have a bottom common to both, i. e. said division-wall. These bottoms 10 are preferably made exchangeable to simplify the insertion and removal of ejectors 12, the double heads 13 of which are forming a part of the inner wall of the several pairs of moulds 11. Each ejector is on the one hand guided in a radial slot 14 of the web of the molding-drum 6 and on the other hand by means of its central slot 15 straddling the division-wall or bottom 10. Figures 1 and 2. These ejectors are radially moved in and out by means of a pair of box-cams 16 rigidly connected with the standards 2 by the aid of tubular supports 17 surrounding the driving-shaft 5. In these box-cams grooves 18 are provided and adapted to engage studs or antifriction-rollers 19 of the ejectors 12, as indicated in Figures 1 and 2. A cover 20, adapted to successively close the moulds 11 after being charged, is attached to a movable traverse 21 guided in slots 22, which slots are arranged in the standards 2 concentrically to the driving-shaft 5. During the compression of the raw material in any one of the pairs of moulds 11 by means of a pair of press-plungers 23 cooperating therewith the cover 20 is compulsorily advanced by said press-plungers. After the formation of the charging-blocks B in said pair of moulds, the mould-cover 20 is automatically returned to its starting-point by means of counter-weights 24 adjustably mounted upon double-armed levers 25, which are loosely seated upon the driving-shaft 5, Figures 1, 2, 4 and 5. On top of the tubular casing 1 a feed-hopper 26 is provided to receive the raw material and successively introduce it at the right moment into said pairs of moulds while pursuing their rotary path.

The press-plungers 23 are arranged in said moulds 11 in pairs and in alignment with each other and with the driving-shaft 5, i. e. horizontally. Each of these plungers carries at its outer end a pin 27 carrying an antifriction-roller 28, which cooperates with a curved wedge-shaped cam 29 fixed to, or forming an integral part of one of the standards 2. These cams are adapted to force the plungers 23 into the moulds containing them, Figures 1, 3 and 4. The outer end of each pin 27 is preferably provided with an antifriction-roller 30 adapted to be guided in one of the diverging cam-grooves 31 of the casing 1 to retract the press-plunger carrying said antifriction-roller after the molding-process of the charging-blocks B has been accomplished.

My improved molding-press operates as follows:

When the molding-drum 6 is rotated in a vertical plane in the direction indicated by the arrows in Figures 1, 2 and 4, the plungers 23 of the ascending pair of moulds 11

are moved outward by the action of the cam-grooves 31 upon the antifriction-rollers 30. As soon as the moulds 11, now fully opened, reach the outlet 32 of the feed-hopper these moulds are charged with raw material, 70 which charging-process is completed before the charged pair of moulds has passed the rear-wall of the feed hopper. When these moulds have reached said rear-wall they are gradually closed by the mould-cover 20 75 abutting against said rear-wall, Figure 2. At the instant the moulds have been completely closed, the antifriction-rollers 30, now acting as a driving means, will strike against abutments 33 of the traverse 21 and 80 thus compel the cover 20 to advance in accordance with the moulds 11 downwardly. Simultaneously herewith the plungers 23 are forcibly moved toward each other from opposite sides by means of the wedge-shaped 85 cams 29 and thus compress the contents of the moulds 11 into charging-blocks B. This operation is completed when the rollers 28 reach the flat extension 34 of the cams 29, Figure 4. At this moment the antifriction-rollers 30 break their contact with the abutments 33, because during the period of compression the plungers 23 were moved inward sufficiently to allow the antifriction-rollers 30 to pass the inner ends of the abutments 95 33. The traverse 21 can now be returned to the rear-wall of the feed-hopper by the action of the counter-weights 24, as will be readily understood. The cover 20 is therefore again in a position to close the next 100 pair of charged moulds as soon as it is passing the rear-wall of the feed-hopper.

During the operations of charging and compression the double head 13 of the ejector 12 belonging to the charged pair of moulds 105 under consideration is kept at rest and remains flush with the inner or bottom-wall of said pair of moulds by guiding the lateral studs or antifriction-rollers 19 of the ejector 12 in the concentric part of the grooves 18 110 of the box-cams 16. This head 13 of the ejector 12 therefore forms a movable part of the moulds 11, in which the cover 20 performs a similar duty. In view of this arrangement the traverse 21 must be strong 115 enough to withstand the pressure exerted in the moulds 11 during the compression of the raw-material, in order to avoid an inadmissible opening of the moulds during the process of compression. The reaction of the 120 plungers 23 on the wedge-shaped cams 29 is transmitted by the standards 2 to the tie-rods 3 which are thereby put under tension and are thus enabled to exempt the foundation of the press from any detrimental 125 downward thrusts or blows.

The charging-blocks B formed in the moulds 11 remain in the latter under pressure until the antifriction-rollers 28 leave the extensions 34. Simultaneously herewith 130

the antifriction-rollers 30 enter the cam-grooves 31 of the tubular casing 1, whereupon the plungers 23 are withdrawn from the blocks B still contained in the moulds 11, because the antifriction-rollers 30 are moved outward by the action of the cam-groove 31. The charging-blocks are now loosely seated in the moulds 11 so that the ejector 12, at this moment moving radially outward under the pressure exerted by one of the eccentric parts of the grooves 18 of the box-cams 16, will gradually and simultaneously push the moulded charging-blocks B out of the moulds 11 into an enlargement 35 of the casing 1 until finally they will drop through the bottom-opening 36 onto a conveyor 37 which transfers them to the kiln or oven, not shown.

While the plungers 23 ascend they are still further retracted until they have reached their extreme end-position, whereas the ejector 12 is drawn fully inward again, so that the several operations described above can be repeated in due succession. It is evident that the remaining pairs of moulds and press-plungers as well as the parts intimately connected with them are made and operated as the similar parts described above, so that with a molding-press constructed in accordance with the embodiment shown and described eight charging-blocks B are produced during each revolution of the molding-drum.

A guard-plate 38 is provided and removably connected with two of the tie-rods 3 in such a manner as to give readily access to the interior of the molding-press, Figure 2.

I claim:—

1. A molding-press of the character described, comprising a molding-drum rotating in a vertical plane, moulds arranged in pairs in the circumference of said molding-drum, press-plungers horizontally disposed in pairs in said pairs of moulds, means for successively charging said pairs of moulds, means for closing each pair of moulds separately when charged, means for forcing the individual plungers of each pair of press-plungers from opposite sides into the pair of moulds charged last, means for ejecting the moulded objects from said pair of moulds, and means for retracting said pair of press-plungers, substantially as set forth.

2. A molding-press of the character described, comprising a molding-drum rotating in a vertical plane, pairs of moulds arranged in the circumference of said molding-drum parallel with the axis of rotation thereof, a common bottom separating the individual moulds of each pair of moulds, a pair of press-plungers disposed in each pair of said moulds, means for charging the individual moulds of the same pair of moulds

simultaneously, means successively closing said pairs of moulds when charged, means for forcing the plungers of the same pair of press-plungers in opposite directions into the charged pair of moulds cooperating therewith, an ejector provided for each pair of moulds and adapted to eject the moulded objects simultaneously therefrom, means for operating said ejector, and means for retracting said pair of press-plungers, substantially as set forth. 70

3. A molding-press of the character described, comprising a molding-drum provided with a plurality of channels transversely arranged in the circumference of said molding-drum, a division-wall bisecting each of said channels to transform the latter into a pair of moulds with a common bottom, a pair of press-plungers horizontally arranged in each of said pairs of moulds, means for successively charging said pairs of moulds, a cover adapted to successively close said pairs of moulds automatically upon being charged, means for forcing the individual plungers of each pair of plungers from opposite sides into the pair of moulds charged last, means on each of said press-plungers adapted to compulsorily advance said cover in accordance with said charged pair of moulds, means for automatically retracting said cover, an ejector arranged in said molding-drum in proximity to each pair of said moulds; cams adapted to keep each ejector alternately stationary, push it radially outward, and retract it during each revolution of said molding-drum; and means for retracting said pairs of press-plungers, substantially as set forth. 80

4. A molding-press of the character described comprising a rotary molding-drum, moulds arranged in pairs in the circumference of said molding-drum, a removable common bottom in each of said pairs of moulds, a pair of press-plungers arranged in alignment with each other in each pair of said moulds, a feed-hopper adapted to successively charge said pairs of moulds, a sliding cover for successively closing said pairs of moulds when charged, stationary wedge-shaped cams adapted to force the individual plungers of each pair of press-plungers into the last charged pair of moulds from opposite sides simultaneously, counterweighted levers for retracting said sliding-cover after the completion of the molding-operation, ejectors each provided with a head for forming parts of the walls of the pair of moulds containing it, stationary box-cams regulating the operations of said ejectors, and means for retracting said pairs of press-plungers, substantially as set forth. 105

5. A molding-press of the character described, comprising a stationary frame, a molding-drum revolvably mounted in said

frame, pairs of moulds arranged in the circumference of said molding-drum; press-plungers operating in pairs in each of said pairs of moulds in alignment with, and in opposition to each other; a feed-hopper for successively charging said pairs of moulds, a sliding cover adapted to successively close said pairs of moulds when charged, wedge-shaped stationary-cams on said frame for forcing the individual plungers of said pairs of plungers successively from opposite sides into the pair of moulds charged last, counter-weighted levers adapted to retract said cover automatically, an ejector disposed in each pair of moulds and adapted to eject therefrom the moulded objects simultaneously, stationary box-cams adapted to successively control the movements of said ejectors, a tubular frame-casing provided with cam-grooves, means on said press-plungers adapted to cooperate with said cam-grooves for retracting said pairs of press-plungers, and a guard-plate detachably connected with said frame, substantially as set forth.

25 6. A molding-press of the character described, comprising a stationary frame, a driving-shaft journalled in said frame, a molding-drum seated on said driving-shaft and rotating in a vertical plane, pairs of moulds arranged in the circumference of said molding-drum, press-plungers horizon-

tally arranged in said pairs of moulds, a cover for successively closing said pairs of moulds, a traverse carrying said cover and guided in slots arranged in said frame concentrically to said driving-shaft, counter-weighted levers revolubly seated upon said driving-shaft and connected with said traverse for automatically retracting said cover, friction reducing-means at the external end of each press-plunger, stationary cams with inclined working-faces cooperating with said friction reducing-means, ejectors arranged within said molding-drum, box-cams likewise arranged within said molding-drum for operating said ejectors, anti-friction-rollers carried by said press-plungers, a tubular casing forming part of said frame and provided with cam-grooves diverging from each other and adapted to engage said anti-friction-rollers for retracting said press-plungers, and a detachable guard-plate for giving readily access to the interior of said molding-press, substantially as set forth.

Signed by me at Hoxter on the Weser, Germany, at this 16, day of August 1921.
